UNITED STATES PATENT OFFICE.

WILLIAM L. SILVEY, OF DAYTON, OHIO.

ELECTRIC-ARC LAMP.

SPECIFICATION forming part of Letters Patent No. 650,872, dated June 5, 1900.

Application filed November 27, 1899. Serial No. 738,347. (No model.)

To all whom it may concern:

Be it known that I, WILLIAM L. SILVEY, a citizen of the United States, and a resident of Dayton, in the county of Montgomery and State of Ohio, have invented certain new and useful Improvements in Arc-Lamps, of which the following is a specification.

My invention relates more particularly to a lamp which may be used for photo-engraving, projecting, or locomotive-headlight purposes, in which a reflector is employed for concentrating and directing the rays of light from the arc in a predetermined direction; and it is the object of this improvement to produce a lamp which will be comparatively simple, very strong and durable, and which will maintain the carbons with relation to each other without their jarring together by heavy shocks. With this object in view I have devised an apparatus as shown in the accompanying drawings, which are made a part hereof, similar letters referring to similar parts throughout, in which—

Figure 1 represents a three-quarter front view in perspective of a complete lamp. Fig. 2 represents a side elevation in perspective with a reflector *y* attached, part of the reflector being broken away in order to show the parts of the lamp inclosed by it. Fig. 3 is a front elevation in perspective with the arc-forming magnets partially wound in order to show their construction. Fig. 4 is a top or plan view in perspective, showing the completed lamp with the parts in their relative positions with relation to each other. Fig. 5 is a horizontal cross-section of Fig. 3 along the dotted line *X* *X*, the view being taken from above. Fig. 6 is a vertical sectional view of the lower carbon and the arc-forming mechanism to which the lower carbon is attached, the parts being enlarged in order to more fully illustrate their construction. Fig. 7 is a vertical sectional view of the parabolic reflector, column *A*, the central support *A'* for the reflector, and the carbons in their relative positions in the reflector, the carbons, carbon-inclosing globe, and carbon-holder being shown in full elevation. Fig. 8 is a vertical section of the top carrying-sleeve *C*, the boss *C'*, the stem *K*, and split nut *K'* and *K''*, showing its relation to the feed-screw *E*, the view being taken on the line *Z* *Z* of Fig. 4.

Fig. 9 is a horizontal cross-section of the sleeve shown in Fig. 8, the stem *K*, split nut *K'* and *K''*, the thumb-nuts *K'''*, and the feed-screw *E*, the view being taken on the dotted line *W* *W* of Fig. 3. Fig. 10 is a view of the electric circuit in diagram, showing the relation of the several parts to each other and to the carbons *t* *t'*, as will be more fully described in the body of the specification. Fig. 11 is a perspective view of the armature by which the carbons are separated in order to form and maintain the arc. Fig. 12 is a cross-section of the cap which covers the upper or top end of the arc-globe; and Fig. 13 is illustrative of the pawl attached to the ratchet-lever *L'''*, by the operation of which a step-by-step rotation is imparted to the ratchet-wheel *L*, and whereby the feed-screw *E* is rotated.

It will be observed that the framework consists of a base *B* and a vertical column *A*, having an enlargement near its center for the reception of the apex of a reflector, all the parts being supported or attached either to the base or to the column. Along the side and parallel with this vertical column *A* is a feed-screw *E*, on which is carried a nut with its attached stem, which controls the motion of a sleeve *C*, which slides on the central column *A* and on which is supported and regulated the upper carbon *t*, the carbon being carried on an arm *C'*, extending from the side of the sleeve and having on its outer end a drilled boss *C'''*, in which is inserted a thumb-screw *C''''*, by which the carbon is held in position. To the feed-screw, which is journaled at each end, is rigidly attached a ratchet-wheel *L*, and journaling on the feed-screw is a ratchet-lever *L'''*, to which is attached a spring-actuated pawl. To the end of the ratchet-lever *L'''* is loosely connected a pitman-rod *M*, one end of which is enlarged into a boss *M''*, which journals on and is actuated by an eccentric, the eccentric being carried on the armature-shaft of a rotary electric motor *H*, the rotation of the armature of this motor being sufficient to impart a step-by-step motion to the ratchet-wheel, the recession of the wheel being prevented by means of a check-pawl *P'* and its actuating-spring *P''*, the spring serving the purpose of keeping the pawl in engagement with the teeth *L'''* on the wheel.

On the lower end of the central column A is journaled sleeve D, by means of which the lower carbon, the arc-forming mechanism, and the adjusting parts are supported and 5 operated. This lower-carbon-carrying sleeve has on one side two projecting lugs D'', between which the regulating-nut D''' is confined. Through the center of this regulating-nut is journaled a regulating-screw d, by 10 which the sleeve D may be raised or lowered on the column and whereby the position of the point of the lower carbon may be regulated with relation to the center of the reflector. To the front part of the sleeve D is 15 fastened a magnet-carrier F, this magnet-carrier being insulated from the sleeve by means of a sheet of mica, hard rubber, or other insulating substance z and suitable insulating-bushings z' around the screws z''. 20 The upper sleeve C, the lower sleeve D, and the column A are preferably made of brass or other non-corrosive metals, while the magnet-carrier or heel-plate F F' F''' (to one side of which is 25 preferably attached an extension F''') for carrying the binding-post Q) should be made of magnetic material, such as cast-iron. Of course this part may be of a composite character and only the heel-plate of the magnet might be of iron; but for the sake of convenience 30 and facilitating the making it is best made of iron. Midway between the magnet-spools S is an extension or boss F'', which is preferably cast as part of the heel-plate magnet. This 35 central boss has a hole in which is loosely fitted and operated a sleeve T, in the lower end of which is screwed a plug T'', the purposes of which are to admit the insertion of the lower carbon t, and when the plug is screwed in place it forms an air-tight joint, jarring loose being 40 prevented by a pin f', which is loosely fitted in two plugs on the front of the boss, the pin passing through a hole in the flange in the loose nut, through which it is free to operate. The upper part of the sleeve T has a thread cut on 45 its outer surface, onto which is screwed a cup-shaped globe-holder U. This globe-holder has an extension or center stem U' projecting up into the globe V, and the nut w, screwing onto this stem, holds the globe in place 50 and draws it down against a packing V', whereby a practically gas-tight chamber is produced. Immediately below the globe-holder U is an armature G, which is held on the sleeve T by means of set-screw G''. At the 55 outer end of this armature G are two arms which project downward into the solenoid-magnets S and in which they are free to move up and down, the two arms serving the double purpose of preventing the sleeve from rotating 60 around its axis and, by the attraction of the coils on the solenoid, to draw the sleeve downward and form an arc between the carbons. Below this armature and surrounding the central sleeve is a spring T', whose purpose 65 is to support the globe, carbon-holder, sleeve, and armature when no current is passing. As soon as the current flows the armature

is attracted downward until it comes in contact with the stationary magnet-cores S''', overcoming the spring T', thereby forming an 70 arc. As soon as the current ceases to circulate in the coils S, which are wrapped around the spools, the spring overcomes the attractive power of the magnets, lifts the carbons upward, and maintains them there until the 75 circuit has been restored. As soon as the circuit has been restored by the carbons t and t' coming in contact with each other the armature is again attracted by the solenoids, drawn downward, and the arc again formed. 80

It will be observed that there is a binding-post Q insulated from the heel-plate magnet. The current enters at this binding-post, passes thence by an insulated wire to one spool of the solenoid, and after traversing its coils it 85 then passes to the other spool, through whose coils it circulates, and from there escapes to the heel-plate or frame by which the solenoids are supported.

On the positive side of the lamp the current enters at the binding-post R, passes thence to the central column A, thence to the sleeve C, the arm C'', and thence to the upper carbon, from which it escapes through the arc to the lower carbon, thence to the sleeve, 90 thence to the magnet-frame and its attached spools, and back to the circuit through the lower binding-post Q, as will be observed in Fig. 10, which is a diagrammatic representation of the circuit. Across the main circuit and in derivation to it is a small motor, which may be of any convenient form, consisting of a field-magnet H and its coils H', an armature N, its commutator and brushes n n', the purpose of this motor being to operate the eccentric and through it, by means of the pitman-rod, the ratchet-lever L''. There is also included in this motor-circuit a supplementary resistance H'', the purposes of which are to compensate for the variations in the circuit according to the kind of circuit on which the lamp is to be operated. 100 105 110

I will now proceed to describe how the lamp operates. Supposing the top and bottom carbons to be separated, the motor, being in derived or shunt circuit across the terminals of the lamp, will receive the full voltage of the circuit. This causes the motor-armature to turn very rapidly, operating the pitman M and the ratchet-wheel L, and causes the feed-screw E to turn, drawing the upper sleeve C down until the upper carbon t' comes in contact with the lower carbon t. As soon as the carbons come in contact with each other the main or arc circuit is completed, and the greater part of the current will then flow from the positive binding-post through the column, upper sleeve, upper carbon, lower carbon, lower sleeve, and solenoids to the negative binding-post, whence it escapes to 115 the circuit. This main circuit being restored weakens the power of the motor to such an extent that it will either entirely stop running or at any rate run very slowly, and the upper 120 125 130 135

carbon is then propelled downward at a rate not to exceed that of its consumption. In case the arc becomes abnormally long the motor becomes energized to a greater extent 5 and operates the carbons more quickly until the equilibrium has been restored.

It will be observed that in making this lamp I have used the inclosed arc, which consists in a glass chamber sealed at the bottom 10 and having a loose cap x on top, the seal being maintained as nearly as possible by means of a piece of asbestos x' , the asbestos washer being maintained in place by means of a stud x'' , attached to and forming part of the cap 15 x . The lower end of the globe is sealed, as before described, by means of a globe-holder U, having a recess or cup in it in which the globe sets, and around the bottom of which and in this recess are the packing V' and a 20 nut w on the inside of the globe, screwing on the stud for drawing the globe down into close proximity to the packing, whereby the chamber is made practically air-tight below. As soon as the current flows through the carbons and the arc is formed in the globe carbon 25 dioxid is generated, which in itself is a non-supporter of combustion. The globe soon becomes filled with this gas, the excess of which will flow out of the top around the positive 30 carbon, but little or no oxygen will be allowed to enter, owing to the higher gravity of the carbonic-acid gas than that of atmospheric air, and in this way very long burning of the lamp is produced, the negative carbon being 35 but very little consumed. In fact by this arrangement it has been found in practice that when the arc has been once formed the light can be burned for several hours without changing the focus materially with relation to 40 the reflector, and should it become necessary to lift the negative carbon it is done by operating the nut D'', by which the sleeve D may be raised or lowered to conform to the center of the reflector. 45 In case it becomes necessary to clean the globe, which occurs occasionally from the accumulation of the carbon dioxid, which forms a white deposit on the inside of the globe, the lower-carbon holder U may be unscrewed 50 from the sleeve T and removed, the globe cleaned, and the carbon-holder U screwed back in position in a few minutes without in any way disturbing any of the connections by which the globe is held in position on the 55 globe-holder. The lower carbon may be unloosened to be raised or lowered by turning the thumb-screw U''', by which the carbon is clamped in position. This globe-holder I wish to make a feature of my claims. By 60 referring to Figs. 2, 3, 8, and 9 it will be observed that the nut K' and K'', which surrounds the feed-screw E, is made split, the two halves being held together by thumb-nuts K'''. The purposes of this split nut 65 are to enable the operator to raise the sleeve C on the column without turning the feed-

screw, and when it is taken into consideration that the threads on this screw are about forty to the inch the utility will be apparent. On one side of the split nut is a turned stem 70 K, which projects into a holder in the boss C'. This stem being round and loose in the holder allows for any irregularity in the feed-screw without binding and is of very great utility, because it is almost impossible to 75 have perfect alinement between the upper or supporting stem J and the base.

By referring to Fig. 7 it will be observed that the column A has a cup-shaped enlargement near its center in which the apex of the 80 reflector y projects and a hole through which the back stem y' of the reflector projects, the reflector being held in position by being drawn into the recess by means of a nut y''. This recess enables me to support the reflector more 85 perfectly and also enables me to make the arms which support the carbons very short, and the lamp will thereby be made more compact, taking up much less room than would be possible were the column set at the side of 90 the reflector, as is customary, or as shown in my Patent No. 403,964, of May 28, 1889, in which a lamp apparatus is shown somewhat in line with the present invention.

It is evident that the most perfect operation 95 of an arc can be produced by the lamp herein shown for the following reason: The feed-screw having about forty threads to the inch and the ratchet-wheel two hundred teeth, it is evident that the motor-armature will have to 100 turn about eight thousand times during the consumption of one inch of carbon. In practice with half-inch carbons of good quality I have found that the upper carbon consumes about eleven sixty-fourths of an inch and the 105 lower carbon consumes about three sixty-fourths of an inch per hour. By examining Fig. 7 in particular it will be observed that the top carbon is set ahead of the bottom one. In other words, they are not axially in line. In practice with a No. 2 reflector, which has a focus of two and one-eighth inches, the top carbon is set one-eighth inch out of alinement, which causes the crater to burn on one side, reflecting the light more perfectly against the apex 115 of the reflector, and besides the point of the carbon is burned away to a bevel of nearly thirty degrees, and as the lower carbon only consumes about three sixty-fourths of an inch per hour and taking into consideration the 120 bevel on the upper carbon it is evident that the lower carbon will operate successfully for several hours without readjusting the arc to the focus of the reflector. Then when it becomes necessary to readjust the focus by turning 125 the thumb-nut D'' the sleeve D is raised and with it the lower carbon and its appurtenances. The lower carbon may be raised independently of this thumb-nut by loosening the thumb-screw U''', by which it is clamped 130 in position in the tube T.

Having described the principal features of

my invention, what I claim as new, and wish to secure by Letters Patent of the United States, is—

1. In an arc-lamp, the combination with the top and bottom carbons, of a reflector, an arc-globe inclosed by it, a column, a carbon-carrier carried by the column, a screw for feeding the upper carbon downward, and a support for the arc-globe consisting of a globe-holder, a tube and a spring, whereby the arc-globe and lower carbon move conjunctively. 70
2. In an arc-lamp, the combination with the top and bottom carbons of a globe having a loose-fitting cover for its top, the lower end having a holder for clamping the globe consisting of a central screw-threaded stem, a split nut on the stem, an annular recess surrounding the stem and a screw-threaded cup on one end of the globe-holder, whereby the holder may be attached to a carbon-tube, and a carbon-clamp and screw for closing the clamp, as set forth. 75
3. In an arc-lamp, the combination with the arc-globe, of a holder therefor having a screw-thread cut in its lower end, an annular recess on its upper end surrounding a central stem, the globe fitted into the recess, and a split nut surrounding the stem inside of the globe, as set forth. 80
4. In an arc-lamp, the combination of a central column, a carbon-carrier mounted on the column, the carbon-carrier having a stem with a hole therein, a feed-screw for operating the carbon-carrier, a split nut engaging the feed-screw, the nut having a stud on one side, the stud entering a hole in the stem in the carbon-carrier, whereby irregularities of alinement between the carbon-carrier and feed-screw are compensated for, as set forth. 85
5. In an arc-lamp, the combination of a round column, with an upper-carbon carrier sliding on the column, a screw, a split nut engaging the screw and the upper-carbon carrier, a ratchet-wheel attached to the screw, a ratchet-lever and pawl, a pitman-rod, one end attached to the ratchet-lever, the other end engaging an eccentric, and an electric motor for actuating the eccentric, whereby rotary motion is imparted to the ratchet-wheel, as set forth. 90
6. In an arc-lamp, the combination of the top and bottom carbons, a globe surrounding the end of the carbons, a screw-rod for feeding one of the carbons, a ratchet-wheel mounted on the screw, a pitman-rod and an eccentric for actuating the ratchet-wheel, and an electric motor for actuating the eccentric, as set forth. 95
7. In an arc-lamp, the combination of the positive and negative carbons, a globe surrounding one end of the carbons, a carrier for the positive carbon, a screw-rod for actuating and supporting the carbon-carrier, a wheel secured to the screw-rod whereby the screw is caused to rotate, and a rotary elec- 100
- tric motor having a crank on its armature-shaft and a pitman-rod operated by the crank, whereby rotary motion is imparted to the wheel on the screw-rod and the carbon is fed, as set forth. 105
8. In an arc-lamp, the combination of a reflector having a fixed focus, a globe inclosed by the reflector, a globe-holder, an electromagnet and its armature, and means whereby the globe is supported and actuated in conjunction with a carbon-point inclosed by the globe, and means whereby the globe is caused to be drawn downward by the electromagnet, when the carbon-points are in contact, as set forth. 110
9. In an arc-lamp, the combination, with an electromagnet having fixed cores, of an armature having dependent points projecting into the helix of the electromagnet, a tube on which the armature is fastened, and a spring for supporting the armature, when inactive, as set forth. 115
10. In an arc-lamp, the combination with the negative carbon pencil of a combined globe-holder and carbon-holder therefor consisting of a central disk, a cup-shaped cavity in its lower end, a carbon-tube screwed into the cup, an annular groove on the upper face of the globe and carbon holder, a tubular screw-threaded stem projecting from the face of the holder, a tube in the central stem, and a clamp-screw for compressing the tube and clamping the carbon, as set forth. 120
11. In an arc-lamp, the combination, of a carbon-carrier having a projecting arm for supporting a carbon, and a projecting tube, with a screw-rod, and a split nut surrounding and engaging the threads of the rod, and a stem attached to one side of the nut and projecting into the tubular projection on the carbon-carrier, as set forth. 125
12. In an arc-lamp, the combination of a base, a column mounted on the base, two sleeves carried by the column, a screw-threaded rod, a wheel on the screw, a lever, a pitman-rod, a crank, and an electric motor for actuating one of the sleeves, the other sleeve actuated by a screw and a nut located between tailpieces on the side of the sleeve, the screw passing through the axis of the nut, as set forth. 130
13. In an arc-lamp, the combination of a base B, column A, sleeve C, screw-threaded rod E journaled in arm J and the base, split nut K' K" having a stem K on one side loosely fitted in a sleeve C', a wheel L fastened to the screw-rod E, and an electric motor having a rotary crank on its armature-shaft, a connecting-rod extending from the crank on the electric motor to a lever whereby continuous rotary motion is transformed from the armature of the electric motor into intermittent rotary motion on the screw-rod, as set forth. 135
14. In an arc-lamp, the combination of a column A having a central cup-shaped part 140

A', a hole A" in the base of the cup, a reflector y whose apex projects into the cup, and a back stem y' on the reflector fitted into the hole A", and a nut y''' for retaining the 5 back stem in position, as set forth.

15. In an arc-lamp, the combination, with a carbon-tube, of an armature therefor, consisting of a straight portion G', a central col-

lar G having set-screws G'''', and tailpieces G'', as set forth.

In testimony whereof I have set my hand in the presence of two subscribing witnesses.
